UNITED STATES PATENT OFFICE

133,105

DESIGN FOR A LADY'S HANDBAG OR THE LIKE

Martin L. Nattenheimer, Chicago, Ill.

Application May 28, 1942, Serial No. 107,031

Term of patent 3½ years

To all whom it may concern:

Be it known that I, Martin L. Nattenheimer, a citizen of the United States, residing at Chicago, in the county of Cook and State of Illinois, have invented a new, original, and ornamental Design for a Lady's Handbag or the Like, of which the following is a specification, reference being had to the accompanying drawing, forming part thereof.

Fig. 1 is a perspective view of a lady's handbag or the like showing my new design, same being shown in open position.

Fig. 2 is a perspective view of the same, showing the bag in closed position and on a reduced scale.

The other side not shown is substantially like the side shown.

I claim:

The ornamental design for a lady's handbag or the like, as shown and described.

MARTIN L. NATTENHEIMER.
